ROSCOE RATCLIFFE, OF NEW BRITAIN, CONNECTICUT, ASSIGNED TO THE TRUCTION
ELECTRIC MFG. CO., OF PLAINVILLE, CONNECTICUT, A CORPORATION OF CON-
NECTICUT.

SWITCH-HANDLE.

1,321,333.

Specification of Letters Patent. Patented Nov. 11, 1919.

Application filed May 26, 1919. Serial No. 239,648.

To all whom it may concern:

Be it known that L. ROSCOE RATCLIFFE, a citizen of the United States of America, residing at New Britain, Connecticut, have 5 invented a new and useful Switch-Handle, of which the following is a specification.

The present invention has reference particularly to operating handles for inclosed switches.

10 The objects of the invention are to provide a simple and inexpensive handle construction which can be readily assembled or combined with the switch mechanism.

Briefly considered, the invention consists 15 of a handle which is journaled in the wall of the box inclosing the switch mechanism and which is held in place by an annular collar provided by expanding or rolling over the metal surrounding an opening in 20 the end of the handle, said collar thereby serving to prevent movement of the handle in one direction and a shoulder on the handle serving to prevent movement in the opposite direction.

25 Various other features of the invention will appear as the specification proceeds.

In the accompanying drawing I have illustrated the invention embodied in one of its practical and commercial forms and 30 wherein:

Figure 1 is a plan view of an inclosed type of switch having the invention incorporated therein.

Fig. 2 is a cross sectional view of the 35 same taken substantially on the plane of line 2-2 of Fig. 1.

Fig. 3 is an enlarged and broken sectional view illustrative of the method of securing the handle in place.

40 The switch mechanism consists in the present disclosure of an insulating base 5 upon which are mounted the fixed contacts 6 and the pivoted switch blades 7 for engagement therewith. These pivoted switch blades are shown connected by a cross bar 8 which in turn is connected by a link 9 and spring 10 with the cranked or offset portion 11 of the operating handle 12.

This operating handle is shown made 50 from a length of rod bent to provide the cranked portion referred to and the operating handle at one end thereof, said rod having straight shaft portions 13, journaled at

opposite ends in the opposite walls of the box 14 which incloses the switch mechanism. 55

The handle is secured in place and held against longitudinal shifting movement by an annular outstanding collar 15 on the end thereof adapted to engage the outer surface of the box wall, and a shoulder 16 arranged 60 to engage the inner surface of the box wall. These positioning shoulders are provided by turning down the end portion of the rod as indicated at 17 to form a reduced journal portion which is rotatably engaged in the 65 bearing opening 18 provided in the box wall. The turning down of the end portion of the shaft leaves the abutment shoulder 16 before described for engagement with the inner face of the box wall. 70

The annular stop shoulder at the outer surface of the box wall is provided by boring or otherwise forming a longitudinal opening 19 in the outer end of the shaft, as indicated in Fig. 3, and then expanding or 75 rolling outwardly the metal surrounding this opening as indicated in dotted lines at 20 in this view to form an outstanding collar.

In assembling the device, it is simply 80 necessary to pass the end of the switch handle through the bearing opening 21 in one side of the box and into engagement with the bearing opening 18 in the opposite side of the box. In this position the reduced portion 85 fits in this latter bearing opening and the bore in the end of the reduced portion is located at the outer face of the box wall in position where it can be readily operated upon by a suitable tool to roll over the 90 metal surrounding the end opening on the shaft. When the end of the shaft is thus expanded, the shaft is firmly secured in place within the box, and is held against longitudinal shifting movement in both directions. This is both a practical and a 95 very inexpensive way of mounting the handle shaft in the box.

I claim:

1. In an inclosed switch, a switch box 100 having journal openings in opposite walls thereof, switch mechanism mounted in said box, an operating shaft connected with the switch mechanism having a bearing at one end in the bearing opening in one wall of 105 the box and having a reduced end portion

bearing in the opening in the opposite wall of the box, a shoulder at the inner end of said reduced portion bearing against the inner surface of the box wall to limit outward movement of the shaft, said reduced portion having a longitudinal opening therein at the outer side of the box wall and the material surrounding said opening being expanded radially outwardly into an annular collar providing a stop engaging the outer face of the wall to limit the inward movement of the operating shaft.

2. In combination, a switch box having a journal opening in the wall thereof, switch mechanism mounted in said box, an operating handle for said switch mechanism having a portion journaled in said bearing opening and provided with an annular shoulder engaging the box wall to limit movement of the handle in one direction, said handle having an opening in the end thereof and the material surrounding said opening being expanded radially outward into an integral annular collar engaging the box wall to limit movement of the handle in the opposite direction.

3. In a switch of the character described, a supporting wall having a bearing opening therein, switch mechanism and an operating

handle for said switch mechanism having a portion journaled in said bearing opening and provided with an outstanding shoulder engaging one face of the supporting wall to limit movement of the handle in one direction, the end of the shaft at the opposite side of said supporting wall having an opening therein and the metal surrounding said opening being expanded outwardly and providing an outstanding collar for engagement with the opposite surface of the supporting wall for limiting movement of the handle in the opposite direction.

4. In a switch of the character described, a supporting wall having a bearing opening therein, switch mechanism and an operating handle for said switch mechanism having a portion journaled in said bearing opening and provided with an outstanding shoulder engaging one face of the supporting wall to limit movement of the handle in one direction, the end of the shaft at the opposite side of said supporting wall having an opening therein and the metal surrounding said opening being expanded outwardly for limiting movement of the handle in the opposite direction.

ROSCOE RATCLIFFE.
